[57] ABSTRACT

A full adder composed essentially of six identical logic circuits each arranged to receive inputs $A_1, A_2, \dots, B_1, B_2, \dots$ and to produce outputs $C = A_1 + A_2 + \dots + B_1 + B_2 + \dots$ and $\bar{C} = \bar{A}_1 + \bar{A}_2 + \dots + (\bar{B}_1 + \bar{B}_2 + \dots)$, the logic circuits being arranged to receive addend input values X_i and $\bar{X}_i$ and carry inputs Z_{i-1} , and their complements, and being arranged in at least two groups of circuits, the first group producing an output carry signal and the second group receiving inputs from the first group and producing an output sum signal.

FULL ADDER

BACKGROUND OF THE INVENTION

The present invention relates to a full adder composed of a relatively small number of identical logic circuits.

The invention is directed to a full adder which forms the sum

$$S_i = X_i \oplus Y_i \oplus (Z_{i-1}) \text{ and the output carry}$$

$$Z_i = (X_i \cdot Y_i) + (X_i \cdot Z_{i-1}) + (Y_i \cdot Z_{i-1})$$

$\oplus$ representing a modulo-2 addition, + the logic OR function and · the logic AND function, the formation of the output carry requiring less time than the sum formation. Such full adders are known and permit rapid processing of carries passing through.

SUMMARY OF THE INVENTION

It is the object of the present invention to construct an improved full adder with the use of logic circuits, particularly of the type disclosed in U.S. Pat. No. 3,504,192, issued to Herbert Stopper on Mar. 31st, 1970, which have at least one first input (A1, A2, ...) and at least one second input (B1, B2, ...) and which link the input values fed to these inputs to form the following output values:

$$C = A1 + A2 + \dots + \overline{B1} + B2 + \dots$$

$$\overline{C} = \overline{A1} + A2 + \dots + (B1 + B2 + \dots)$$

The present invention consists in that the addends X_i , Y_i and their complements $\overline{X}_i$, $\overline{Y}_i$ are fed to a total of four inputs of a first group of logic circuits which form first output values $X_i + Y_i$, $\overline{X}_i + \overline{Y}_i$, $X_i \cdot \overline{Y}_i$, $\overline{X}_i \cdot Y_i$; that a second group of the logic circuits forms, from at least two of the first output values and from the input carry Z_{i-1} and its complement $\overline{Z}_{i-1}$, the output carry Z_i and second output values; and that a logic circuit forms the sum S_i from two of the second output values.

BRIEF DESCRIPTION OF THE DRAWINGS

FIG. 1a is a block circuit diagram of a basic logic circuit employed in circuits according to the invention.

FIG. 1b is a simplified symbolic representation of the circuit of FIG. 1a.

FIG. 2 is a schematic diagram, using the symbolic representation of FIG. 1b, of one embodiment of a full adder according to the present invention.

FIG. 3 is a view similar to that of FIG. 2 of another embodiment of a full adder according to the present invention.

FIG. 4 is a schematic diagram of a practical embodiment of the logic circuit of FIG. 1a which is known, per se.

DESCRIPTION OF THE PREFERRED EMBODIMENTS

A logic circuit which links input values A and B into output values $C = A + \overline{B}$ and $\overline{C} = \overline{A} \cdot B$, where the input value A can be replaced by the disjunctively linked values A1, A2, ... and the input value B can be replaced by the disjunctively linked values B1, B2, ... so that the previously mentioned linkage equations result, is disclosed in the above-mentioned U.S. Pat. No. 3,504,192. The logic circuit diagram of such a circuit having at least four inputs A1, A2, B1, B2 is shown in FIG. 1a. FIG. 1b shows a simplified symbol for the circuit shown in FIG. 1a which will be used in illustrating circuits according to the invention.

In terms of logic function, the circuit of FIGS. 1a and 1b consists of two OR gates each receiving all of the A or B inputs and an ORNOT gate having its direct input connected to the A-input gate and its negated input connected to the B-input gate. The ORNOT gate has a direct output C and a complementary output $\overline{C}$. The logic circuit could also be considered as an OR gate receiving inputs A, a NOR gate receiving inputs B, and an OR gate receiving the outputs of the first two gates and having a direct function output and a complementary, or negated, function output.

FIG. 2 shows one stage of one preferred embodiment of the full adder according to the present invention. The index i indicates the bit location; a higher value of i corresponds to a higher bit location. The full adder of FIG. 2 contains seven logic circuits L1 to L7 each identical with the circuit of FIG. 1; however, only logic circuits L1 to L6 will initially be discussed below. The individual logic circuits each have four inputs A1, A2, B1, B2. The interconnection of the logic circuits and the association of input and output signal values with the inputs $A1\mu$, $A2\mu$, $B1\mu$, $B2\mu$, where $\mu = 1 \dots 6$ and corresponds to the logic circuit reference numeral, and outputs $C\mu$, $\overline{C}\mu$ is accomplished as follows:

$$\text{Circuit L1: } A11 = X_i, B11 = \overline{Y}_i$$

$$\text{Circuit L2: } A12 = \overline{X}_i, B12 = Y_i$$

$$\text{Circuit L3: } A13 = X_{i-1}, B13 = \overline{C}_i, B23 = \overline{C}_{i-1}$$

$$\text{Circuit L4: } A14 = \overline{C}_i, A24 = \overline{C}_i, B14 = Z_{i-1}$$

$$\text{Circuit L5: } A15 = \overline{C}_i, B15 = \overline{Z}_{i-1}, B25 = C_i, C5 = Z_i$$

$$\overline{C}5 = \overline{Z}_i$$

$$\text{Circuit L6: } A16 = \overline{C}_3, B16 = C_4, C6 = \overline{S}_i, \overline{C}6 = S_i$$

The following logic values are then available at the individual outputs of the logic circuits:

$$C1 = X_i + Y_i = P_i$$

$$\overline{C}1 = \overline{X}_i \cdot \overline{Y}_i = \overline{P}_i$$

$$C2 = \overline{X}_i + \overline{Y}_i = \overline{G}_i$$

$$\overline{C}2 = X_i \cdot Y_i = G_i$$

$$C3 = Z_{i-1} + (C1 \cdot C2)$$

$$C3 = Z_{i-1} \cdot (C1 + C2) = [(X_i + Y_i) + (X_i \cdot Y_i)] \cdot \overline{Z}_{i-1}$$

$$C4 = C2 + \overline{C}1 + Z_{i-1}$$

$$C4 = C2 \cdot C1 \cdot Z_{i-1} = (\overline{X}_i + \overline{Y}_i) \cdot (X_i + Y_i) \cdot Z_{i-1}$$

$$C5 = C2 + (C1 \cdot Z_{i-1}) = (X_i \cdot Y_i) + [Z_{i-1} \cdot (X_i + Y_i)] = \overline{Z}_i$$

$$C5 = C2 \cdot (\overline{C}1 + Z_{i-1}) = Z_i$$

$$C6 = C3 + C4 = [(X_i \cdot Y_i) + (\overline{X}_i \cdot \overline{Y}_i)]$$

$$= \overline{Z}_{i-1} + [(X_i + Y_i) \cdot (\overline{X}_i + \overline{Y}_i) \cdot Z_{i-1}] = \overline{S}_i$$

$$C6 = C3 \cdot C4$$

$$= S_i$$

For producing the above values it is assumed that the value fed to input A2 of logic circuit L6, i.e. input A26, is $\overline{T} = 0$, where T is a clock pulse value and $\overline{T}$ is its complement, or inverted value. The logic values appearing at outputs $C1$, $\overline{C}1$, $C2$, $\overline{C}2$ are represented by the abbreviated symbols P_i , $\overline{P}_i$, G_i , $\overline{G}_i$, respectively.

The carry Z_i requires less time for its information in this full adder than the sum S_i inasmuch as the carry of the previous stage, or more exactly speaking its complement $\overline{Z}_{i-1}$, must pass through only one logic circuit before the carry Z_i of the present stage is formed. At the output $\overline{C}6$ the sum S_i for the stage is available.

Since the full adder operates asynchronously, i.e. without the addition of a clock pulse, it will be advisable in many cases to provide a memory in which the value of sum S_i can be stored. For this purpose a further logic circuit L7 is provided having its input A17 connected with the output $\overline{C}6$, its input B17 connected with its output $C7$, and its input B27 receiving a clock pulse signal T. At the same time, the inverted clock pulse signal $\overline{T}$ is fed to input A26 of logic circuit L6.

With this arrangement, signal $S_i \cdot T$ is available at output $\overline{C}6$. Upon the occurrence of a clock pulse T, this signal is transferred into the flipflop formed by logic circuit L7, at whose output C7 it is available for the duration of the clock pulse and during the subsequent clock pulse interval. The connection of a circuit such as logic circuit L7 as such a flipflop is also disclosed in U.S. Pat. No. 3,504,192, at column 4, line 73, to column 5, line 2.

FIG. 3 shows another embodiment of the full adder according to the present invention which is constructed in a manner similar to that of the circuit of FIG. 2 of six logic circuits L1 to L6 and a logic circuit L7 connected to act as a flipflop. Here, too, the values P_i , $\overline{P}_i$, G_i , $\overline{G}_i$ are available at the outputs of the logic circuits L1 and L2. The interconnection of logic circuits L1 to L6 and the association of input values and output values

with the inputs and outputs is accomplished in the following manner:

Circuit L1: $A11 = X_i$; $B11 = \bar{Y}_i$
 Circuit L2: $A12 = \bar{X}_i$; $B12 = Y_i$
 Circuit L3: $A13 = Z_{i-1}$; $A23 = \bar{C}1$; $B13 = C2$
 Circuit L4: $A14 = \bar{Z}_{i-1}$; $B14 = \bar{C}2$; $B24 = \bar{C}1$
 Circuit L5: $A15 = \bar{C}2$; $B15 = \bar{Z}_{i-1}$; $B25 = \bar{C}1$
 Circuit L6: $A26 = \bar{T}$; $B16 = \bar{C}4$; $B26 = \bar{C}3$
 $C5 = Z_i$; $\bar{C}5 = \bar{Z}_i$; $C6 = S_i$; $\bar{C}6 = \bar{S}_i$

At the individual outputs of the logic circuits the following values are available ($\bar{T}$ is again assumed to be 0):

$$C1 = X_i + Y_i = P_i$$

$$\bar{C}1 = \bar{X}_i \cdot \bar{Y}_i = \bar{P}_i$$

$$C2 = \bar{X}_i + \bar{Y}_i = \bar{G}_i$$

$$C3 = C1 + C2 + Z_i$$

$$C3 = C1 \cdot C2 \cdot \bar{Z}_{i-1}$$

$$C4 = \bar{Z}_{i-1} + (C1 \cdot C2)$$

$$C4 = Z_{i-1} \cdot (\bar{C}1 + \bar{C}2)$$

$$C5 = \bar{C}2 + (Z_{i-1} \cdot C1) = X_i \cdot Y_i + (X_i + Y_i) \cdot Z_{i-1} = Z_i$$

$$C5 = C2 \cdot (\bar{Z}_{i-1} + \bar{C}1) = \bar{Z}_i$$

$$C6 = C3 \cdot C4 = \bar{S}_i$$

$$C6 = \bar{C}3 + \bar{C}4 = X_i \cdot \bar{Y}_i \cdot \bar{Z}_{i-1} + \bar{X}_i \cdot Y_i \cdot \bar{Z}_{i-1}$$

$$+ \bar{X}_i \cdot \bar{Y}_i \cdot Z_{i-1} + X_i \cdot Y_i \cdot Z_{i-1} = S_i$$

As regards the speed of the carry formation and the transfer of sum S_i into the memory formed by logic circuit L7, the same applies as that stated with respect to the full adder of FIG. 2.

The logic circuits may be constructed in different ways. Advantageously the circuits are constructed in the manner disclosed in U.S. Pat. No. 3,504,192. One such circuit is illustrated herein in FIG. 4 and includes two transistors T1 and T2 which are connected in a current conducting manner with their emitters connected via a source of current I to one terminal of a voltage supply source providing a voltage -U and their collector resistors R1 connected to the other terminal of the voltage supply source. Connected in series with the control circuit of the one transistor T2 is a voltage source having a lower voltage than the voltage swing of the control signals applied to the transistors, i.e. the voltage swing between the logic values 0 and 1, the voltage provided by the series-connected voltage source preferably being one-half of such control signal voltage swing.

The voltage source which is connected in series with the control circuit of transistor T2 is represented in FIG. 4 by a resistor R2 and a current source circuit Q2 which produces a current of such an amplitude to flow through resistor R2 that the desired voltage drop is produced therein. The inputs of the circuit are A1, A2, B1 and B2 and the outputs of the circuit are C and $\bar{C}$. A more detailed description of this circuit can be found in U.S. Pat. No. 3,504,192, the circuit itself being illustrated in FIG. 8a of that patent.

A plurality or all of the logic circuits required for the construction of the full adder may be accommodated in a single integrated circuit. It is here advantageous to bring one or a plurality of the values P_i , $\bar{P}_i$, G_i , $\bar{G}_i$ to individual connecting points where they can be tapped and are available for other logic connections.

The unused inputs of the logic circuit of FIGS. 2 and 3 are connected, depending on the circuit system employed, to a voltage corresponding to logic 0 or are left unconnected. The latter is possible in the circuit of FIG. 4 where the level cor-

responding to logic 1 is 0 volt and the level corresponding to logic 0 is a negative voltage.

It will be understood that the above description of the present invention is susceptible to various modifications, changes and adaptations and the same are intended to be comprehended within the meaning and range of equivalents of the appended claims.

What is claimed is:

1. A binary full adder which forms the output sum

$$S_i = X_i \oplus Y_i \oplus Z_{i-1}$$

and the output carry

15

$$Z_i = X_i \cdot Y_i + X_i \cdot Z_{i-1} + Y_i \cdot Z_{i-1}$$

from received values X_i , $\bar{X}_i$, Y_i , $\bar{Y}_i$, Z_{i-1} and $\bar{Z}_{i-1}$, the formation of the output carry taking less time than the output sum formation, said adder comprising a plurality of logic circuits each having a plurality of first inputs A1, A2, ..., a plurality of second inputs B1, B2, ..., a direct function output C and a corresponding negated function output $\bar{C}$, and linkage means interconnecting said inputs and said outputs for establishing the relationships:

25

$$C = A1 + A2 + \bar{B}1 + \bar{B}2$$

$$\bar{C} = \bar{A}1 + \bar{A}2 + (B1 + B2), \text{ wherein}$$

30

there is a first group of said logic circuits having a total of four of their said inputs connected to each to receive a respective one of the values X_i , $\bar{X}_i$, Y_i and $\bar{Y}_i$ and arranged for producing at each of four of their said outputs a respective one of first output values $X_i + Y_i$, $\bar{X}_i + \bar{Y}_i$, $X_i \cdot Y_i$ and $\bar{X}_i \cdot \bar{Y}_i$.

35

there is a second group of said logic circuits having inputs connected to two of said outputs of said first group and other inputs connected to receive the values Z_{i-1} and $\bar{Z}_{i-1}$ and arranged for producing the output carry Z_i at the output of one of said logic circuits of said second group and a plurality of second output values which are functions of X_i , $\bar{X}_i$ and Z_{i-1} at selected outputs of said logic circuits of said second group; and a further one of said logic circuits has inputs connected to receive the second output values for producing the output sum S_i at one of its outputs.

40

2. An arrangement as defined in claim 1 wherein said first and second groups of logic circuits and said further logic circuit consist of a total of not more than six of said logic circuits.

45

3. An arrangement as defined in claim 2 wherein said first and second groups and said further logic circuit consist of six logic circuits $L\mu$, where μ is 1, 2, 3, 4, 5 or 6 for each respective logic circuit, each of said logic circuits having two first inputs $A1\mu$ and $A2\mu$, two second inputs $B1\mu$ and $B2\mu$ and two outputs $C\mu$ and $\bar{C}\mu$, said inputs and outputs of said six logic circuits being connected as follows:

$$A11 = X_i; \quad B11 = \bar{Y}_i;$$

$$A12 = \bar{X}_i; \quad B12 = Y_i;$$

$$A13 = Z_{i-1}; \quad B13 = \bar{C}2; \quad B23 = \bar{C}1;$$

$$A14 = \bar{C}2; \quad B14 = Z_{i-1}; \quad A24 = \bar{C}1;$$

$$A15 = \bar{C}2; \quad B15 = \bar{Z}_{i-1}; \quad B25 = \bar{C}1;$$

$$A16 = \bar{C}3; \quad B16 = C4$$

$$Z_i = C5; \quad \bar{Z}_i = \bar{C}5; \quad S_i = \bar{C}6; \quad \bar{S}_i = C6$$

70

4. An arrangement as defined in claim 2 wherein said first and second groups and said further logic circuit consist of six logic circuits $L\mu$, where μ is 1, 2, 3, 4, 5, or 6 for each respective logic circuit, each said logic circuit having two first inputs $A1\mu$ and $A2\mu$, two second inputs $B1\mu$ and $B2\mu$ and two out-

75

puts $C\mu$ and $\overline{C}\mu$, said inputs and outputs of said six logic circuits being connected in the following manner:

$$\begin{aligned}
 A11 &= X_i; & B11 &= \overline{Y}_i \\
 A12 &= \overline{X}_i; & B12 &= Y_i \\
 A13 &= Z_{i-1}; & B13 &= C2 & A23 &= \overline{C1} \\
 A14 &= \overline{Z}_{i-1}; & B14 &= \overline{C2} & B24 &= \overline{C1} \\
 A15 &= \overline{C2}; & B15 &= \overline{Z}_{i-1} & B25 &= \overline{C1} \\
 & & B16 &= \overline{C4} & B26 &= \overline{C3} \\
 Z_i &= C5; & \overline{Z}_i &= \overline{C5}; & S_i &= \overline{C6}; & \overline{S}_i &= C6
 \end{aligned}$$

5. An arrangement as defined in claim 1 wherein there is an additional one of said logic circuits having one of its inputs connected to that one of said outputs of said further logic circuit providing the output sum S_t , said output $\overline{C}$ of said additional logic circuit being connected to one of said second inputs of said additional logic circuit, another second input of said additional logic circuit being connected to receive a train of clock pulses, and a first input of said further logic circuit, to

which input no other signal is applied, is connected to receive a train of pulses constituting the complement of said clock pulses.

6. An arrangement as defined in claim 1 wherein each of 5 said logic circuits comprises two transistors, the emitters of which are connected together and are also connected through a current supply circuit to the one pole of a voltage supply source and the collector resistors of which are connected to the other pole of said voltage supply source, and a voltage 10 source connected in series with the control circuit of one said transistor, said voltage source producing a voltage which is lower than the voltage swing of the control signal supplied to said transistors.

7. An arrangement as defined in claim 1 wherein said adder 15 is constructed according to integrated circuit techniques and at least several of said logic circuits are contained in a unitary integrated circuit.

8. An arrangement as defined in claim 1 further comprising 20 at least one externally available connecting terminal to which one of said four outputs of said first group of logic circuits is connected for permitting its associated one of said first output values to be applied to an external circuit.
